ADJUSTING MEANS FOR SPRING BALANCES

Algol Larson, Bronx, N. Y., assignor to Unique Balance Co., Inc., New York, N. Y., a corporation of Illinois

Application August 20, 1947, Serial No. 769,631

5 Claims. (Cl. 16—197)

1

The present invention relates to window sash balances of the type commonly referred to as spiral balances, that is, of the type utilizing spiral springs to compensate for the weight of the window in moving it from open to a normally closed position.

More particularly, the invention relates to the general form of window sash balances shown in United States Letters Patent Nos. 1,926,951 and 2,041,646 and embodies, more specifically, an improved structure by means of which the tension of the balancing spring is adjusted with facility from time to time as desired and while the balance mechanism is mounted in its normal operating position.

In existing forms of window sash balances of the type above referred to, when the balance has once been installed in its normal operating position, it is rather difficult to effect any adjustment of the tension of the spring in the balance. Such adjustments can only be made by dismounting the mechanism temporarily from its normal operating position.

In accordance with the present invention a window sash balance is provided wherein the tension of the spring in the sash balance may be conveniently adjusted without disturbing the mounting of the balance in any manner.

Other and further objects of the invention will be apparent as it is described in greater detail in connection with the accompanying drawings, wherein

Figure 1 is a perspective view of a window provided with sash balances constructed in accordance with the present invention;

Figure 2 is a view in transverse cross-section, taken on line 2—2 of Figure 1, and looking in the direction of the arrows;

Figure 3 is a view in vertical cross-section, taken on line 3—3 of Figure 2, and looking in the direction of the arrows;

Figure 4 is a partial view in side elevation, taken on plane 4—4 of Figure 3, and looking in the direction of the arrows;

Figure 5 is a view in cross-section, taken on line 5—5 of Figure 4, and looking in the direction of the arrows;

Figure 6 is a view in cross-section, taken on line 6—6 of Figure 4, and looking in the direction of the arrows;

Figure 7 is an exploded view showing the elements of the adjusting mechanism constructed in accordance with the present invention;

Figure 8 is a view, partly broken away and in section, showing the elements of Figure 7 in assembled relation;

Figure 9 is a view similar to Figure 8, showing the way in which adjustment of the spring is effected while the window sash balance is mounted in its normal operating position.

2

Referring to the above drawings, a window frame is indicated generally at 10 as having upper and lower sashes 11 and 12, respectively. For each of the sashes 11 and 12, there is provided a sash balance mechanism 13, which is shown in greater detail in Figure 3. Sash balance mechanism comprises an elongated tube 14, within which a spiral spring 15 is received. The spring 15 is secured at its lower end to a sleeve 16 that is journaled within a balancing member 17 secured to the lower end of tube 14. A spiral strip 18 is received within an elongated co-operating slot 16' within the tube 16 and is anchored at 19 to a hinge pin carried by a plate 20, which is formed with a flange 21 and is adapted to be nailed or suitably secured to the sash.

The upper end of the spring 15 is inserted over a ferrule 22 to which it is securely clamped, the upper end of the ferrule being upset and formed with a downwardly projecting flange 23, the lower edge of which is formed with teeth 24. Suitably spaced apertures 25 are provided in the upper end of the ferrule 22 and are adapted to receive a nail or pin 26 in order to advance the teeth 24 in one direction or another.

A stationary ferrule 27 is received within the upper end of the tube 14 and may be secured thereto by a tube or eye 28 which may also serve to receive the attaching screw 29. The lower end of the ferrule 27 is formed with an inwardly and upwardly extending flange 30 that is formed with teeth 31 that are adapted to co-operate with teeth 24. The tube or ferrule 27 is formed with a cutaway portion 32 that is sufficiently long circumferentially of the tube 14 to expose two of the apertures 25 to view, as illustrated in Figure 4. Overlying the cutaway portion 32 in the ferrule 27 there is provided a similar cutaway portion 33 in the outer tube 14, each of the cutaway portions including an offset notch 34 adapted to receive the pin 26 to lock the adjusting mechanism in a desired adjusted position.

In operation, the tension of the spring 15 may either be increased or decreased in the following manner. If the tension of the spring is to be increased, the nail or pin 26 is removed from the position illustrated in Figure 3 and is inserted in the left-hand aperture 25, as appearing in Figures 4, 8, and 9. The pin is then moved over to the right, at which time the notches 24 ride up over the notches 34 and drop down into engaging position in which the spring adjustment is held by the notches. Further adjustment is accomplished by removing the pin from its previous aperture and inserting it into the aperture that has come to the left of the slot 33 and again advancing it to the right and into the position shown in Figure 9. This may be continued until the tension of the spring is sufficiently corrected. If the tension of the spring is to be reduced,

the pin 26 is inserted in the aperture 25 at the right of the slot 33 as shown in Figures 4, 8, and 9, the ferrule 22 lifted until the notches 24 and 31 disengage, and then the tension of the spring is permitted to move the ferrule 22 and pin 26 to the left, at which time the notches 24 will drop down and engage the notches 31.

Further relief of the tension of the spring may be accomplished by continuing this operation until the desired tension is obtained.

After the desired adjustment has been accomplished, the pin or nail 26 is inserted in the notch 34, and the ferrule 22 is thus prevented from rising, insuring that the notches 24 and 31 remain continually in engagement.

It is to be observed that an important feature of this invention is the provision of means to maintain a desired adjustment of the balance mechanism while the device is in a normal non-assembled position, such, for example, as the condition in which it is sold and prior to its installation. This is accomplished as will be apparent in Figure 3, by providing the spiral rod or strip member 18 of such length as to be received between the tube 14 and the eyelet 28, as illustrated in dot-and-dash lines. In this position, it is impossible to change the adjustment of the spring.

From the foregoing, it will be seen that the adjustment of the sash balance is accomplished with facility while the balance is mounted in its operating position, and the structure is simple and inexpensive to manufacture and is effective in operation.

While the invention has been described with reference to the specific structure shown in the accompanying drawings, it is not to be limited save as defined in the appended claims.

I claim:

1. Adjusting mechanism for a sash balance for a window having a coiled torsion spring received within a tube, one end of which spring is secured to a nut and spiral strip member adapted to be secured to a sash for varying the tension of the spring with movement of the sash, said adjusting mechanism comprising a ferrule to which the other end of the spring is secured, interengaging ratchet teeth carried by the tube and ferrule, said teeth being urged into engagement by said spring, an elongated aperture formed in the side of the tube, a lock aperture in the tube above the top of the ferrule, a plurality of apertures in the ferrule, and a pin adapted to be inserted in the plurality of apertures to adjust the ratchet teeth and in the lock aperture to lock the ferrule in adjusted position.

2. Adjusting mechanism for a sash balance for a window having a coiled torsion spring received within a tube, one end of which spring is secured to a nut and spiral strip member adapted to be secured to a sash for varying the tension of the spring with movement of the sash, said adjusting mechanism comprising a ferrule to which the other end of the spring is secured, an upset flanged portion on the end of the ferrule remote from the spring, ratchet teeth formed on the edge of the flanged portion adjacent the spring, a hollow tube section secured within the first named tube and having an upset and inwardly projecting flange formed at one end thereof and having ratchet teeth formed thereon to co-operate with the first named ratchet teeth, and means to adjust the ratchet teeth of the ferrule with respect to those of the tube section.

3. Adjusting mechanism for a sash balance for

a window having a coiled torsion spring received within a tube, one end of which spring is secured to a nut and spiral strip member adapted to be secured to a sash for varying the tension of the spring with movement of the sash, said adjusting mechanism comprising a ferrule to which the other end of the spring is secured, an upset flanged portion on the end of the ferrule remote from the spring, ratchet teeth formed on the edge of the flanged portion adjacent the spring, a hollow tube section secured within the first named tube and having an upset and inwardly projecting flange formed at one end thereof and having ratchet teeth formed thereon to co-operate with the first named ratchet teeth, an elongated opening in the tube section, a plurality of apertures in the ferrule, at least two of which are exposed simultaneously through the elongated opening, and a pin to engage the apertures to move the ferrule with respect to the tube section.

4. Adjusting mechanism for a sash balance for a window having a coiled torsion spring received within a tube, one end of which spring is secured to a nut and spiral strip member adapted to be secured to a sash for varying the tension of the spring with movement of the sash, said adjusting mechanism comprising a ferrule to which the other end of the spring is secured, an upset flanged portion on the end of the ferrule remote from the spring, ratchet teeth formed on the edge of the flanged portion adjacent the spring, a hollow tube section secured within the first named tube and having an upset and inwardly projecting flange formed at one end thereof and having ratchet teeth formed thereon to co-operate with the first named ratchet teeth, an elongated opening in the tube section, a plurality of apertures in the ferrule, at least two of which are exposed simultaneously through the elongated opening, and a pin to engage the apertures to move the ferrule with respect to the tube section and to engage the lock opening in the tube section to lock the ferrule in ratchet engaging position.

5. Adjusting mechanism for a sash balance for a window having a coiled torsion spring received within a tube, one end of which spring is secured to a nut and spiral strip member adapted to be secured to a sash for varying the tension of the spring with movement of the sash, said adjusting mechanism comprising a ferrule to which the other end of the spring is secured, interengaging means between the ferrule and tube, said tube being formed with an aperture in the side thereof, means operable through the aperture to release the interengaging means and vary the tension of the spring, an eyelet in the tube at the end thereof remote from the nut, and said spiral strip member being of such length as to extend between the eyelet and tube when the strip member is fully advanced into the tube.
